FOUNTAIN PAINTBRUSH WITH ROTATABLE
AND YIELDING GUIDE FOR STRIPING

Willard J. Gebien, Chicago, Ill.

Application May 29, 1946, Serial No. 672,923

6 Claims. (Cl. 15—131.05)

1

This invention relates to a fountain paint brush, and more particularly to such a brush adapted to be utilized particularly in connection with cut-in or striping work in exterior or interior dwelling painting, or the like, or in similar instances where painting of the surface at an angle to an adjacent surface is desired, while protecting the other surface.

A primary object of the invention is the provision of an improved fountain brush of this character provided with means whereby a wall surface adjacent a surface to be painted, and set at an angle thereto, or flush therewith, may be protected from the overflow of paint from the surface to be painted.

A still further object of the invention is the provision of such a brush characterized by a slide member, which serves as a guard for the surface to be protected, and which at the same time serves as a cover for the bristles of the brush when the brush is not being used.

Still another object of the invention is the provision of an improved means for feeding paint from the reservoir of the paint brush to the bristles, only at such times as the brush is actually in use.

Still another object is the provision of such a device which will be sturdy and durable in construction, reliable and efficient in operation, and relatively simple and inexpensive to manufacture and assemble.

Other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a top plan view of one form of brush embodying features of the instant invention.

Figure 2 is a sectional view taken substantially along the line 2—2 of Figure 1 as viewed in the direction indicated by the arrows, certain parts thereof being indicated in different position of adjustment.

Figure 3 is a sectional detail view taken substantially along the line 3—3 of Figure 2 as viewed in the direction indicated by the arrows.

Figure 4 is a sectional view taken substantially along the line 4—4 of Figure 3 as viewed in the direction indicated by the arrows.

Figure 5 is a fragmentary bottom view of a portion of the device showing a constructional detail.

2

Figure 6 is a fragmentary bottom view of a further portion of the device showing additional constructional detail.

Figure 7 is a sectional view taken substantially along the line 7—7 of Figure 8 as viewed in the direction indicated by the arrows.

Figure 8 is a fragmentary sectional view taken substantially through the center line of the device, but showing certain parts in different positions of adjustment, and

Figure 9 is a bottom plan view of a constructional detail, certain parts thereof being removed.

Figure 10 is a side elevation of the reciprocating guide and shield.

Similar reference characters refer to similar parts throughout the several views of the drawings.

Having reference now to the drawings, the device is comprised of a casing 10, provided with a hollow interior 11 in which is positioned a compression spring 12. One end of the spring 12 bears against the end 13 of the casing, and the other abuts a cup-shaped metal guide 14, to which is secured a metal washer 15 and a washer 16. The lower end of the casing is threaded as at 17, and has engaged therewith a threaded cap 18, removable to permit filling of the device with paint.

A ball chain 19 is secured to a suitable bolt 20 extending through the guide 14 and the washers 15 and 16 and is secured in position as by a nut 21. The opposite end of ball chain 19 extends through an aperture 22 in the end 13 of the casing, and terminates in a cap 23. As best shown in Figures 7 and 8 the aperture 22 is key-hole-shaped, and the ball chain 19 is adapted, when the member 23 is pulled to compress the spring 12, to engage in the narrowed or reduced portion of the aperture to hold the spring in compressed position to permit refilling of the device when the cap 18 is removed.

Secured to, or integral with the casing 10 is an extending projection 25, provided with an interior recess 26 in communication, through a passage 28 with the interior 11 of the handle 10. The recess 26 contains a valve seat 27, normally closed by a valve 29 biased by a compression spring 30, the ball being engaged by a needle 31, the lower extremity of which engages a leaf 32 pivotally secured in lugs 33 in a recess 34 in the lower portion of projection 25. The leaf 32 comprises a portion of a double coil spring member, including upper and lower extending arms 35 and 36 and a spring loop 37. Legs 36 are adapted to engage the transverse surface 40 of a slide mem-

3

ber generally indicated at 41, within the upper portion of which is contained a block 42 fixed to the projection 25, as described later, and having a pair of passageways 43 extending therethrough. The passageways 43 extend in the form of tubes 44 to a transversely extending tube 45 in communication with the passage through the valve seat 29, the needle 31 extending upwardly through a suitable aperture in the passage 45. Bristles 46 are secured in any desired manner to 10 in the lower space of the block 42, and the arrangement is thus such that when the ball valve 29 is opened, in a manner to be more fully described hereinafter, paint is forced through the passage 26 by the bias of spring 12 and thence into the 15 passageway 46 and through the tubes 44 to the bristles 46, thus making the paint available for use.

The slide 41 includes side walls 50 and end walls 51, adapted when in extended position, as shown in Figure 2 to completely surround the bristles 46. As best shown in Figures 2 and 5 one of the side walls 50 is provided with an upstanding lug 52 provided with an elongated slot 53 adapted to be engaged by the end of a bolt 54 which extends through a circular disk 55 and a wedge-shaped spacer block 56. The end of the bolt comprises an elongated member which may be turned to permit the same to be withdrawn from the slot, or at right angles thereto will serve to hold the circular disk in position on the wall 50. The disk attachment may be utilized if desired to serve as a guide during the painting of rough surfaces. As best shown in Figure 6, an aperture 57 is cut in the projection 25 at a point in alignment with the lug 52, to permit the same to be retracted therewithin when the slide 41 is slid inwardly with respect thereto.

From the foregoing the operation of the device should be obvious. When it is desired to utilize the brush for painting a surface and protecting adjacent surfaces, as when striping, the brush is pressed against the surface to be painted, which action forces the slide 41 inwardly with respect to the projection 25 against the influence of spring arms 35 and 36 opening the valve 29 against the action of its spring 30, whereupon paint is permitted to flow under the pressure applied by spring 12, to the valve 29, and thence by passage 45 and tubes 44 which are received in aligned passages 43 in the brush block 42, from whence liquid is fed to the bristles. Obviously, when the circular guide is utilized the pressure on the guide effects the same function. During the recession of the slide into the projection, the upper end of member 52 is received within the notch 57.

When the device is no longer being utilized it will be apparent that the spring 35 serves to bias the slide downwardly against the block 42 60 in such manner as to completely cover the bristles 46, simultaneously shutting the valve.

As shown best in Figures 2 and 10 a pair of laterally extending, spaced retainer guides 58 are secured in any desired manner transverse the member 25 and across the passage 34, these retainer guides being received in elongated slots 59 formed in the reciprocating member 41 to limit the movement thereof. These guides extend through and serve to support and retain 70 the brush holder 42.

In this connection it is to be noted that the tubes 44 extend a material distance into the

4

passageways 43, and that the slide is apertured to permit movement with respect to the tubes 44.

From the foregoing it will now be seen that there is herein provided an improved fountain brush, accomplishing all the objects of this invention, and others, including many advantages of great practical utility and commercial importance.

As many embodiments may be made of this inventive concept, and as many modifications may be made in the embodiment thereinbefore shown and described, it is to be understood that all matter herein is to be interpreted merely as illustrative and not in a limiting sense.

I claim:

1. In a paint brush having a handle, a liquid reservoir carried by said handle, means for applying pressure to the liquid in said reservoir, a projection secured to said handle having a chamber opening from the end thereof, a block mounted in said chamber, bristles carried by said block and extending from the open end of said chamber, a slide surrounding said block and slideable in said chamber, the lower end of said slide comprising a guard surrounding said bristles, fastening means extending laterally from said block for fixedly mounting the latter in spaced relation to the walls of said chamber, elongated slots in said slide for receiving said fastening means, a conduit extending from said reservoir to said block and into said bristles and a valve in said conduit.

2. The combination of claim 1 wherein the lower end of said guard has a support bracket extending laterally therefrom, a guide disk journaled on said bracket, the wall of said chamber being notched at its lower end to receive said bracket in the retracted position of said slide.

3. The combination of claim 1 including spring means between the closed end of said chamber and the adjacent end of said slide for urging said slide outwardly of said chamber.

4. The combination of claim 3 wherein said spring means includes a member for actuating said valve, said member being engageable and operable by said slide in the inward position thereof, for opening said valve.

5. The combination of claim 1 wherein said conduit includes passages in said block, tubes carried by said projection and slidably received in said passages, said valve means controlling the flow of liquid into said tubes.

6. The combination of claim 5 wherein said valve is disposed in a recess in said projection, a stem on said valve extending into said chamber, and means in said chamber for operating said valve in response to movement of said slide.

WILLARD J. GEBIEN.
